UNITED STATES PATENT OFFICE

112,059

DESIGN FOR A KNIFE

John Didio, Buffalo, N. Y.

Application September 20, 1938, Serial No. 79,997

Term of patent 14 years

To all whom it may concern:

Be it known that I, John Didio, a citizen of the United States, residing at Buffalo, in the county of Erie and State of New York, have invented a new, original, and ornamental Design for a Knife, of which the following is a specification, reference being had to the accompanying drawing, forming part thereof.

In the drawing:

Fig. 1 is a side elevation of a knife viewed from one side thereof, embodying my new design.

Fig. 2 is a top plan view thereof.

Fig. 3 is an end elevation of the same viewed from its handle.

I claim:

The ornamental design for a knife, as shown.

JOHN DIDIO.
